CLAIM

The ornamental design for a soother, as shown and described.

DESCRIPTION

The patent or application file contains at least one drawing executed in color. Copies of this patent or patent application publication with color drawing(s) will be provided by the Office upon request and payment of the necessary fee.

1. Soother

1.1 is a top perspective view of the soother showing my new design;

1.2 is a right side elevational view thereof;

1.3 is a left side elevational view thereof;

1.4 is a front elevational view thereof;

1.5 is a rear elevational view thereof;

1.6 is a top plan view thereof; and

1.7 is a bottom plan view thereof.

The portions of the soother shown in the color yellow form no part of the claimed design.
